(57) **CLAIM**

The ornamental design for a bow string capture and release device, as shown and described.

DESCRIPTION

FIG. 1 is a rear view of a bow string capture and release device showing my new design;

FIG. 2 is a right side elevation view thereof;

FIG. 3 is a front elevational view thereof;

FIG. 4 is a top plan view thereof;

FIG. 5 is a left side elevational view thereof;

FIG. 6 is a bottom plan view thereof;

FIG. 7 is a rear elevational view of a second embodiment of a bow string capture and release device showing my new design;

FIG. 8 is a right side elevational view of FIG. 7;

FIG. 9 is a front elevational view of FIG. 7;

FIG. 10 is a left side elevational view of FIG. 7; and;

FIG. 11 is a bottom plan view of FIG. 7.

The cross hatching shown in FIGS. 1, 3, 4, 6, 7, 9 and 11 represents circumferential knurling of the cylinder depicted in FIGS. 5 and 10.

The broken lines shown in the drawings on FIGS. 5 and 10 represent a boundary between claimed and unclaimed portions of the design and form no part thereof.
